ENGINE

Carl F. Bachle, Grosse Pointe, Mich., assignor, by
mesne assignments, to Reconstruction Finance
Corporation, Detroit, Mich.

Application January 25, 1940, Serial No. 315,531

3 Claims. (Cl. 123—171)

This invention relates to engines and more particularly to the cylinder head structure of an air cooled aircraft engine and more particularly to an improved construction for dissipating heat from the exhaust valve guide carried by the cylinder head and also for dissipating heat from certain critical portions of the cylinder head structure.

It has been observed that it is more difficult to cool an in-line air cooled engine than the radial type of engine. It is more difficult to control the flow of air around the cylinder head and therefore it has not been desirable to build air cooled in-line aircraft engines except for those engines of relatively low power output. It has been found possible however, to improve the cooling of low powered output aircraft engines by providing means circulating the cooling air in closer relation with respect to the combustion chamber and the engine valves.

An object of the present invention is to provide for improved engine performance by providing an improved arrangement for dissipating heat from the cylinder head structure.

A further object of the present invention is to improve engine operating characteristics by providing an air tunnel extending between the engine valves in close proximity to the combustion chamber, and by incorporating therewith an arrangement of cooling fins providing a maximum of area for the dissipation of heat, and more particularly it will be observed that this air tunnel extends intermediate the rocker box and the combustion chamber.

More particularly, the objects of the present invention are best accomplished by providing an air tunnel whose total area in cross-section relative to the cylinder bore area is such as to provide a maximum of heat dissipation, and more particularly I provide a construction in which a plurality of cooling fins extend inwardly of said air tunnel directly from the hottest stressed portion of the cylinder head overlying the engine combustion chamber adjacent to the cylinder axis. Also, this present construction provides adequate cooling for the exhaust valve guide and substantially prevents distortion of the valve seats under the influence of heat originating in the combustion chamber.

For a more detailed understanding of the invention, reference may be had to the accompanying drawings illustrating preferred embodiments of the invention, and in which:

Fig. 1 is a fragmentary sectional view through an engine cylinder and head structure taken sub-

stantially in a plane containing the axes of the intake and exhaust valves,

Fig. 2 is a fragmentary sectional view taken on the line 2—2 of Fig. 1,

Fig. 3 is a plan elevational view of a small power output aircraft engine, and

Fig. 4 is a sectional view through the engine cylinder illustrating a modified construction.

The engine illustrated in Figs. 1 and 2, and on which the present invention is applied, is indicated as a whole by the reference character A and comprises in general a crankcase 10, to which is secured a plurality of cylinders 11. These cylinders 11 are secured in any suitable manner to the engine crankcase, and a cylinder head structure 12, which carries suitable valve guides 13, is secured to the cylinder structure in a conventional manner. These valve guides 13 support intake and exhaust valves 14 and 15 respectively, which are preferably moved axially inwardly of the cylinder. The cylinder head structure has formed integrally therewith a rocker box structure 16 sometimes designated as a housing structure for supporting the valve actuating mechanism. The valves 14 and 15 have stem portions 18 projecting into the rocker box 16 which may be actuated by any suitable form of mechanism and said valves are yieldingly closed on the valve seats by the valve springs 19. The cylinder head structure also includes a combustion chamber 20, the cylinder head structure including a wall 21, which carries the said valve seats 22 and which overlies the open end of the cylinder 11.

The present engine is of the air cooled type and the cylinder is provided with suitable fins for dissipating heat produced by the combustion of gases within the cylinder. The cylinder head carries a plurality of cooling fins 23 which extend substantially around the combustion chamber or it might be said that they substantially encircle the cylinder. The cylinder head has intake and exhaust passages 24 and 25 associated with the intake and exhaust valves 14 and 15, and each of these passages is so arranged as to be formed within the cylinder head structure and bounded by wall portions 26 having cooling fins which substantially encircle same.

In most cases it is preferable to have an additional fin area associated with the exhaust valve and exhaust passage 25 in order to provide adequate cooling for the exhaust valve guide. In the present construction the cylinder head is provided with an air tunnel 27 which is extended through the cylinder head structure, which tun-

nel is open at both ends and is constructed to extend intermediate the intake and exhaust valves. This air tunnel 27 conducts cooling air across the central portion of the combustion chamber 20 and serves to bring the cooling air across the wall portion overlying the combustion chamber for obtaining a maximum dissipation of heat. It is found desirable to provide cooling fins 28 which project upwardly from wall 21 and extend longitudinally of the air tunnel in order to provide an adequate fin area for dissipating heat. It will also be noted that the fins 29 substantially encircle the exhaust valve and exhaust passage 25, and these fins project into the tunnel as at 29a. It will be noted that these fins 29a project inwardly of the tunnel and are contained in planes extending substantially normal to the valve axes whereas the fins 28 lie in planes extending substantially parallel to the valve axes.

It may be further noted that the tunnel 27 extends intermediate the rocker box portion of the cylinder head and the ceiling 21 of the combustion chamber 20. It will thus be seen that there is provided an air tunnel through the cylinder head structure which supports the engine intake and exhaust valves. This type of engine is generally referred to as an "overhead valve engine," because the valves are actuated by valve mechanism from a point overlying the open end of the cylinder. In L-head engines the valves are not exposed to such critical temperatures and they are, furthermore, placed where effective cooling may be conveniently had. In an overhead valve engine the valves are not so conveniently located, and it is found that an air tunnel substantially as shown in the present application provides a maximum of cooling areas for dissipating heat absorbed by the cylinder head from the combustion of gases in the combustion chamber, and thus the improved cooling arrangement as herein described, provides for more efficient engine operation and has resulted in much improved engine performance over those heretofore produced.

It will be observed that the air tunnel 27 illustrated in the accompanying drawings, is preferably constructed substantially rectangular in cross-section and thus a considerable portion of the cylinder head wall 21, that forms the ceiling of the combustion chamber 20, is exposed to the cooling influence of the air flowing through the air tunnel. The central portion of the wall 21, indicated by the reference character 21a is substantially the hottest stressed portion of the entire cylinder head. This wall 21 also supports the valve seats 22 and if not adequately cooled, the valve seats will tend to become distorted. It will be noted that the base of the fins 28 are closely adjacent to this wall portion 21a and serve to dissipate a maximum of heat from the wall 21.

The present air tunnel construction has another distinct advantage over previous constructions in that substantially the whole length of the exhaust valve guide is exposed to the cooling influences of the air stream flowing through the air tunnel 27. It will be noted that the wall 40 is of a minimum practical thickness, and separates the exhaust valve guide 13 from the air tunnel, and that this relatively thin wall 40 extends along substantially the entire axial length of said valve guide. The fins 29a within the tunnel 27 serve to dissipate heat from the exhaust passage 25 and the exhaust valve guide 13 thereby lowering the temperature of the metal. The present air

tunnel provides for a substantial flow of a large volume of air into direct heat transference relation to interior portions of the cylinder head structure and has proved quite advantageous in that this construction has resulted in improved engine performance.

It has been determined that the cooling of the interior portions of the cylinder head may be most efficiently obtained with an air tunnel having a minimum cross-sectional area of from one-fifth ($\frac{1}{5}$) to one-fifteenth ($\frac{1}{15}$) the area of the cylinder bore. The construction illustrated in Fig. 1 shows an air tunnel whose cross-sectional area within the fin at the narrowest part, in plane A—A is approximately one-tenth ($\frac{1}{10}$) the area of the cylinder bore. The construction illustrated in Fig. 4 shows fins 28a, which extend relatively higher and quite close to the bottom wall 30 of the rocker box, and has an effective cross-sectional area which is approximately one-fifth ($\frac{1}{5}$) the area of the cylinder bore.

It will be evident that maximum engine efficiency is obtained by constructing an air tunnel whose shape and size is such as to effect a substantially direct heat transfer from critical areas or parts such as the exhaust valve guide and the central wall portion 21a of the combustion chamber. A relatively small air flow is of very little practical use, and the proportions I have set forth above have proved to be adequate and to result in much improved engine performance.

The above improved cooling system is particularly applicable to an overhead valve engine of the in-line type in which the valves open inwardly and substantially axially of the engine cylinder. Although only one form of the engine has been described in detail and illustrated in the accompanying drawings, it will be apparent that various changes and modifications may be made therein without departing from the spirit of the invention or from the scope of the appended claims.

I claim:

1. In an internal combustion engine having a cylinder, a cylinder head structure overlying the cylinder and constructed of an integral structure defining a combustion chamber overlying the cylinder and a rocker box overlying the combustion chamber, overhead intake and exhaust valves supported by said cylinder head and opening axially inwardly of the cylinder and including valve stems projecting into the interior of said rocker box, valve actuating mechanism supported in said rocker box, said cylinder head having intake and exhaust passages terminating respectively in intake and exhaust ports opening into said combustion chamber, and an air tunnel extending across the central portion of the cylinder intermediate the rocker box and combustion chamber and overlying a portion of said intake and exhaust ports, said cylinder head having valve guide bores supporting valve guides which support said valves, said tunnel constructed to provide a wall of minimum thickness substantially parallel to said exhaust valve guide and for substantially the whole length of said exhaust valve guide bore, and a plurality of cooling fins lying in planes extending normal to the cylinder and valve axes, encircling said exhaust passage and carried around said wall portion separating the exhaust valve guide from the air tunnel.

2. In an internal combustion engine having a cylinder, a cylinder head structure overlying the cylinder and constructed of an integral structure defining a combustion chamber overlying

the cylinder and a rocker box overlying the combustion chamber, overhead intake and exhaust valves supported by said cylinder head and opening axially inwardly of the cylinder and including valve stems projecting into the interior of said rocker box, valve actuating mechanism supported in said rocker box, said cylinder head having intake and exhaust passages terminating respectively in intake and exhaust ports opening into said combustion chamber, and an air tunnel extending across the central portion of the cylinder intermediate the rocker box and combustion chamber and overlying a portion of said intake and exhaust ports, and a plurality of fins carried by said cylinder head and including fins extending into said tunnel from the wall overlying the combustion chamber in planes extending parallel to the cylinder axis and other cooling fins extending into said tunnel from the wall surrounding the exhaust passage in planes extending normal to the cylinder axis.

3. In an internal combustion engine having a cylinder, a cylinder head structure overlying the

cylinder and cooperating therewith to define a combustion chamber, intake and exhaust valves supported by said cylinder head and opening axially inwardly of the cylinder, said cylinder head having valve guide bores supporting intake and exhaust valve guides, said cylinder head provided with a substantially rectangular air tunnel open at both ends and extending between said valves and across the central portion of said combustion chamber substantially normal to the cylinder axis, said air tunnel constructed and arranged to provide a side wall section adjacent to said exhaust valve guide bore, the aforesaid side wall section extending substantially parallel with respect to said exhaust valve guide bore and constructed with a minimum thickness for substantially the entire length of the exhaust valve guide bore whereby to place substantially the total length of said exhaust valve guide bore in direct heat transference relation to the air stream flowing through said air tunnel.

CARL F. BACHLE.
